UNITED STATES PATENT OFFICE

155,288

DESIGN FOR A COMBINED COFFEE BREWER COVER AND STAND

Carl W. Hellberg, Chicago, Ill.

Application May 10, 1947, Serial No. 138,976

Term of patent 14 years

(Cl. D44—26)

To all whom it may concern:

Be it known that I, Carl W. Hellberg, a citizen of the United States, residing in Chicago, Cook County, State of Illinois, have invented a new, original, and ornamental Design for a Combined Coffee Brewer Cover and Stand, of which the following is a specification, reference being had to the accompanying drawing, forming a part thereof.

Fig. 1 is a perspective view of a combined coffee brewer cover and stand, showing my design;

Fig. 2 is a plan view; and

Fig. 3 is a central vertical sectional view thereof.

I claim:

The ornamental design for a combined coffee brewer cover and stand, as shown.

CARL W. HELLBERG.
